PACKBOARD

Alexander C. H. Weiss, Chicago, Ill., and Russell W. Ehlers, Silver Spring, Md., assignors to the United States of America as represented by the Secretary of the Army

Application May 14, 1952, Serial No. 19,707

Term of patent 3½ years

(Cl. D87—5)

To all whom it may concern:

Be it known that we, Alexander C. H. Weiss and Russell W. Ehlers, both citizens of the United States, residing, respectively, at Chicago, in the county of Cook and State of Illinois, and at Silver Spring, in the county of Montgomery and State of Maryland, have invented a new, original, and ornamental Design for a Packboard, of which the following is a specification, reference being had to the accompanying drawings, forming a part thereof.

Figure 1 is a rear perspective view of a packboard embodying our invention.

Figure 2 is a front perspective view of the packboard.

Figure 3 is a rear elevation of the same.

Figure 4 is a bottom end elevation of the packboard.

Figure 5 is a horizontal cross section on line 5—5 of Figure 3.

Figure 6 is a horizontal cross section on line 6—6 of Figure 3.

Figure 7 is a front elevation of the packboard. Figure 8 is a side elevation of the same, and,

Figure 9 is a central vertical longitudinal section on line 9—9 of Figure 7.

We claim:

The ornamental design for a packboard, substantially as shown.

ALEXANDER C. H. WEISS.
RUSSELL W. EHLERS.
